UNITED STATES PATENT OFFICE.

JOHN PATRICK LEO DONLEVY, OF LONDON, ENGLAND.

ELECTRICAL TRANSMITTING AND RECEIVING APPARATUS.

No. 821,931.

Specification of Letters Patent.

Patented May 29, 1906.

Application filed August 21, 1905. Serial No. 275,095.

To all whom it may concern:

Be it known that I, JOHN PATRICK LEO DONLEVY, a subject of the King of Great Britain, residing at London, England, have invented new and useful Improvements in Electrical Transmitting and Receiving Apparatus, of which the following is a specification.

This invention relates to electrical transmitting and receiving instruments, the objects of such invention being to provide means whereby, first, the Morse or such like codes may be dispensed with when such apparatus is employed for conveying ordinary messages; second, a message may be transmitted or read by persons possessing no technical knowledge; third, any convenient number of letters, words, or signs may be caused to appear upon the dial or the receiver simultaneously or independently, and such letters, words, or signs may be capable of remaining visible during any required period of time.

I will now describe my invention with reference to the accompanying drawings, in which like letters denote like parts.

Figure 1 is a front elevation of a transmitting and receiving apparatus constructed in accordance with my invention. Fig. 2 is a plan of the keyboard of the transmitting apparatus. Fig. 3 is a transverse section of the combined apparatus, and Fig. 4 is a vertical section of the receiving apparatus.

It will be understood that one complete instrument consists of a keyboard for transmitting messages and a receiver, which may be attached thereto or separate therefrom, according to requirements, one such complete instrument being required at each station with which it is desired to be in communication, the keyboards of each instrument being connected directly or indirectly by a commutator to the receiver portion of the other instruments, a battery or other source of current being in circuit therewith.

45 The keyboard is composed of a casing *a*, within which the key-stems *b* are pivoted.

The keys, preferably ten in number, are spaced and arranged to suit the natural position taken by the finger-tips. By this means the fingers need never leave their respective keys while operating, thus rendering it possible for a blind person to transmit messages or for those who see to keep their eyes fixed upon the copy. Each key-stem is provided with a circuit-closing device, consisting of a spring-mounted set-screw *c* and

contact-patch *d*, the circuits being completed through the binding-screws *e*. The springs *f* are for returning the keys to their normal position. The keys are pivoted at *g* and are provided with suitable stops and pads in the ordinary manner.

The sight-reading receiving device is contained within a casing *h*, so constructed as to stand upon the keyboard-casing *a* or apart from same, if desired. The said device consists of a type-drum *i*, upon the surface of which letters, words, or signs are arranged in rows and rings, the casing *h*, as shown in the illustration, being pierced with sight-holes *k* at such intervals that a letter, word, or sign in every alternate ring may be brought opposite to a sight-hole. Should I elect to employ five sight-holes, the drum will have ten rings forming five rows of letters, words, or signs. Thus an axial movement of the drum to and fro equal to the pitch of the said rings will cause alternate rings to take up their position opposite the sight-holes. Each sight-hole is furnished with a suitably-balanced shutter *l*, such shutter being carried upon the pivoted arm *m*, such arm being in continuation of or attached to the armature *n* of the magnet *o*. Each magnet *o* is in circuit with its respective circuit-closing device and key 85 in the distant keyboard. Thus by depressing the keys respectively in circuit with the shutters such shutter may be opened simultaneously or successively. Each shutter upon being opened exposes to view the letter, word, or sign immediately opposed to the sight-hole common to such shutter. Axial movement is given to the type-drum *i* by means of the pivoted arm *p*, which arm terminates in the forked pin-provided end *q*. The pins upon the end *q* engage a groove *r* formed upon a portion of the drum *i*. The pivoted arm *p* is attached to or integral with the armature *t*, the weight of such armature being generally sufficient to retain the type-drum *i* at its normal lateral position, in which position it is shown in the drawings. The electromagnet *u*, which is in circuit with the key in the keyboard assigned thereto, is so situated as to be capable of operating the armature *t*. Thus by depressing this said key the magnet *u* attracts the armature *t*, thereby operating the pivoted arm *p*, with the result that the drum *i* is laterally traversed to such an extent that the intermediate letters, words, or signs thereon are brought in line in the sight-holes. As soon as the circuit

is broken by the release of the key the magnet *u* no longer attracts the armature *t*, which falls to its normal position, at the same time returning the drum *i* also to its normal position.

Oscillating or rotary motion of the drum *i*, which is irrespective and independent of the traversing movement above indicated, is effected by the following device: The drum *i* is shown in the drawings at its normal position. The sector-rack *v* is in mesh with the pinion *w*, which pinion is fixed upon the drum-spindle *s*. The sector-rack is so pivoted that upon oscillating or rocking motion being imparted thereto the drum is oscillated or rotated in either direction. The sector-rack is continued below the pivot and terminates in the transverse plate *x*. Four pivoted and suspended armatures, situated two on each side of the transverse plate *x*, are provided each with an extension-piece *y*, each extension-piece being provided with a set-screw *z*. The set-screws *z* are set to engage the plate *x*. The armatures swing clear when their respective magnets are inoperative, but when attracted by their magnets they cause the transverse plate *x* to rock, thereby causing the sector-rack *v* to rock also. These four magnets are in circuit each with its specific key within the keyboard. Thus if the key in circuit with magnet 3 is closed the armature 1 is attracted thereby, throwing its extension-piece over, and thereby rotating the drum in one direction, and if the circuit of magnet 4 be closed the armature 2 will rotate the drum in an opposite direction.

The armature 1 and magnets 3 are in duplicate situated in parallel. So, also, are the armatures 2 and magnets 4. The set-screw *z* of the armature 1 being so set that the drum shall be caused to revolve to the extent of one line of letters, words, or signs, and the set-screw *z* of the duplicate armature 1 being so set that the drum shall be caused to revolve to the extent of two lines of letters, words, or signs, the armatures 2 are arranged to operate the drum similarly in an opposite direction. Springs 5 return the sector-rack *v* to its normal position when the armatures 1 and 2 cease to be operative.

I claim—

1. Electrical transmitting and receiving

apparatus comprising a detachable keyboard-transmitter and sight-reading receiver, the said transmitter consisting essentially of key-actuated electrical devices, and the receiver of a series of rotatable and longitudinally-movable drums carrying the letters, words or signs, of sight-holes controlled by shutters, and means for effecting the movements of the said drums and shutters from the keyboard of the transmitter, substantially as described. 55

2. An electrical transmitting and receiving apparatus comprising a keyboard having spring-keys and electrical contact devices in connection therewith, a casing, having sight-holes therein shutters for said holes, type-drums in said casing and means for rotating and traversing the drums and operating the shutters from the keyboard. 60

3. An electrical transmitting and receiving apparatus comprising a detachable keyboard having spring-keys, contact devices carried by said keys, a casing having sight-holes therein, shutters for said holes, a pivoted arm for each shutter, an armature connected to said arm, magnets controlling the armatures, a type-drum in said casing, an arm connected to said drum for giving the drum a longitudinal movement, a magnet and armature for operating said arms, a pinion on the drum, a sector-rack engaging with the pinion and armatures and magnets for rocking said sector-rack, all of said magnets being controlled from the keyboard. 70

4. An electrical transmitting and receiving apparatus comprising a sight-reading device contained within a casing and consisting of a series of drums upon which letters, signs, or words are intermittently displayed through sight-holes pierced in the casing aforesaid, means for independently traversing and rotating such drum to any desired position, a shutter for each sight-hole and independent means for operating such shutters individually or collectively, substantially as and for the purposes herein described. 85

In testimony whereof I have signed my name to this specification in the presence of two subscribing witnesses.

JOHN PATRICK LEO DONLEVY.
